HOSIERY

Ralph Beuter, Karl Max Marschner, and Alfred Marschner, Philadelphia, Pa.

Application May 5, 1939, Serial No. 271,826

8 Claims. (Cl. 66—182)

This invention relates to a new and useful improvement in hosiery, and more specifically in the construction of the foot thereof, with the object of eliminating a number of half sizes of foot length now considered essential to a complete line of hosiery, and at the same time securing proper fit as to length over the same range, and, in addition, better fit and greater comfort in the toe and instep.

At the present time ladies' high-grade hosiery is made in half sizes as to length running from, say, 7½ to 11 or a total of eight different foot lengths. In addition, some manufacturers, recognizing that there is a wide variation in the height of the instep, make each size in two or more instep heights. In this way, perhaps the most important variations in the human foot have been provided for to some extent, but others have been ignored, such, for example, as variations in width across the toes and the heel, and abnormal, but by no means uncommon, departures from standard of any two or more of these dimensions.

By this invention it should be possible to limit such hosiery to four sizes, say, 8, 9, 10 and 11 to obtain a size-range equivalent to the eight sizes heretofore mentioned, and to a single size of instep, heel and toe, and yet attain improved fit and greater comfort.

The stocking selected for purposes of illustration and description herein is assumed to be a full-fashioned flat knit stocking, although the invention is not limited thereto. Such a stocking is shown in the accompanying drawing, in which—

Figure 1 illustrates the foot of a full-fashioned stocking, which may be generally standard in construction with the exception of the heel or toe, or both;

Figure 2 is an enlarged fragment of the fabric of the heel or toe, or both; and

Figure 3 is a similar fragment showing a structural modification.

As shown, the foot may consist of the usual reinforced heel, sole and toe portions, 1, 2 and 3, respectively, and the unreinforced instep portion 4. All of these parts may have the usual or any desired shape and may be knit, generally speaking, in the usual way. However, the structure of the heel and toe is novel.

For example, the heel 1, which is usually composed of heavily reinforced fabric of uniform simple loop structure, is by this invention knit in the following way: When the heel tabs are started a few courses 5 of the usual reinforced fabric composed of simple interlinked loops may be pro-

duced, the length of loop employed being generally somewhat longer than that of the unreinforced leg and instep to permit the inclusion of reinforcing yarns, and yet short enough to obtain fabric of the desired tightness. These courses are followed by one or more courses 6 of a yarn having substantially greater inherent elasticity. The loop length may be the same as that of previous courses, or it may be different. Preferably, although not necessarily, it should be such that the fabric of this course or courses will be of substantially the same tightness as that of the other courses, so that the loop length employed will be determined primarily by the size of the yarn employed.

When these courses are completed several more reinforced courses 7 similar to courses 5 are knit with the yarns employed in courses 5, and these, in turn, are followed by one or more courses 8 of the same elastic yarn, and so on, until the heel tabs are completed.

Similarly, the reinforced toes may be started in the usual way by several courses 5 of the usual reinforced fabric, which is followed in turn by one or more courses 6 of a yarn having substantially greater elasticity, and so on until the toe is completed. In other words, the construction of the toe may be the same as that of the heel although the number, loop length, etc., of the courses may be different.

In this way a stocking foot is produced which, because of the inclusion of the relatively elastic courses in the heel or toe, or both, is much more elastic lengthwise, and also has much greater circumferential elasticity in the toe and much greater longitudinal elasticity in the heel. Because of the lengthwise elasticity of the foot, stockings knit to sizes 8, 9 and 10 will fit feet normally requiring sizes from 7½ to 10½, thus reducing the required number of foot lengths by at least 50%. Also, because of the greater circumferential elasticity of the toe each stocking will accommodate itself to a wide variation of foot width in this portion so that a snug fit can be obtained at the toe irrespective of the width of the foot there. The circumferential elasticity of the heel permits it to adapt itself to various widths of heel without pulling the other parts of the foot and instep out of their proper position, and the vertical elasticity of the heel insures that any unnecessary slack in the length of the foot will be taken up there. In addition, the combined horizontal and vertical elasticity of the heel is also effective in the diagonal direction so that de-

partures from normal in other parts of the foot will be accommodated without pulling the instep fabric out of position.

In short, the elasticity of the toe and heel obtained by this invention produces a stocking foot which is extremely flexible and which will fit perfectly feet which would normally require several different sizes as to length and still different sizes as to instep height. It is no longer necessary, for example, for one having an unusually high instep to obtain the necessary room in this part by wearing a stocking which is altogether too long for the foot, and folding under the toe, which is a very common practice. In addition, perfect fit around the toe and at the heel is assured.

In view of the fact that the elastic courses described above may be lacking in desirable strength and may differ in appearance from the rest of the heel and toe fabric, the above structure may be modified, if desired, by simultaneously knitting with the elastic yarn, a yarn 9 similar to that employed in the adjacent sections. Since these yarns are knit together they will, of course, have the same loop length, but because one yarn is more elastic than the other, the loops of the less elastic yarn will normally be loose and will not come under tension until the loops of the elastic yarn have been stretched. In this way the elastic yarn is strengthened by reinforcement and the elastic courses made to resemble more closely the other courses. This structure is shown in Figure 3, wherein the relatively inelastic yarn which accompanies the more elastic yarn is indicated by the numeral 9.

35 We claim:

1. A stocking foot having heel and toe portions composed of a plurality of relatively narrow bands of tight knit reinforced fabric, each band of which is joined to the following band by at least one course of substantially the same tightness composed of a yarn having materially greater inherent elasticity than the yarn of said bands.

2. A stocking foot having a heel portion composed of a plurality of relatively narrow bands of tight knit reinforced fabric, each band of which is joined to the following band by at least one course of substantially the same tightness com-

posed of a yarn having materially greater inherent elasticity than the yarn of said bands.

3. A stocking foot having a toe portion composed of a plurality of relatively narrow bands of tight knit reinforced fabric, each band of which is joined to the following band by at least one course of substantially the same tightness composed of a yarn having materially greater inherent elasticity than the yarn of said bands.

4. A stocking foot having a toe portion composed of a plurality of series of courses of reinforced fabric, each series of which is joined to the following series by at least one course composed of a yarn having materially greater inherent elasticity than the yarn of said series, and a reinforcing yarn of normal elasticity.

5. The method of knitting the heel portion of a stocking which consists of first knitting a series of tight reinforced courses, then knitting at least one course of substantially the same tightness of a yarn of substantially greater inherent elasticity and then repeating in the order indicated as many times as desired.

6. The method of knitting the toe portion of a stocking which consists of first knitting a series of tight reinforced courses, then knitting at least one course of substantially the same tightness of a yarn of substantially greater inherent elasticity and then repeating in the order indicated as many times as desired.

7. The method of knitting the heel portion of a stocking, which consists of first knitting a series of reinforced courses, then knitting at least one course of a yarn of substantially greater inherent elasticity reinforced by a yarn of normal elasticity, and then repeating in the order indicated as many times as desired.

8. The method of knitting a toe portion of a stocking, which consists of first knitting a series of reinforced courses, then knitting at least one course of a yarn of substantially greater elasticity reinforced by another yarn of normal elasticity, and then repeating in the order indicated as many times as desired.
